UNITED STATES PATENT OFFICE.

EDWARD BRAGG, OF FARMERVILLE, LOUISIANA.

MILKING-STOOL.

1,220,316.

Specification of Letters Patent.

Patented Mar. 27, 1917.

Application filed June 27, 1916. Serial No. 106,198.

To all whom it may concern:

Be it known that I, EDWARD BRAGG, a citizen of the United States, residing at Farmerville, in the parish of Union and State of Louisiana, have invented certain new and useful Improvements in Milking-Stools; and I do hereby declare the following to be a full, clear, and exact description of the invention, such as will enable others skilled in the art to which it appertains to make and use the same.

This invention relates to new and useful improvements in milking stools and the principal object of the invention is to provide a light and portable stool which may be strapped to the body of the user in order that it may be readily placed in position for use.

Another object of the invention is to provide a strong and durable stool for supporting the user in a comfortable position during the milking operation.

A still further object of the invention is to provide a device which is particularly simple in construction and may be adjusted to persons of various sizes.

With these and other objects in view, the invention consists in the novel combination and arrangement of parts which will be fully set forth in the following specification and accompanying drawing, in which:

Figure 1 is a perspective view of the milking stool constructed in accordance with this invention.

Fig. 2 is an enlarged detail fragmentary sectional view illustrating the joint between the seat and the standard, and

Fig. 3 is an enlarged fragmentary sectional view through the lower end of the standard.

Referring to the drawing the numeral 1 designates a standard of the ordinary construction which preferably is formed out of a light strong wood and is circular in cross section as clearly illustrated in the drawing. The lower end of the standard is provided with a bore 2 which is internally screw threaded and adapted to receive the threaded extension 3 of the foot 4. A suitable fer-

rule 5 surrounds the lower terminal of the standard 1 and is adapted to prevent the same from splitting. The upper end of the standard is provided with a rectangular projection 6 having formed therein a plurality of transverse openings 7 through which the belt 8 passes and it will thus be seen that the belt may be adjusted to various heights from the seat according to the desire of the occupants thereof.

Formed in the standard intermediate its ends and extending transversely thereof is a suitable opening 9 which may be of any desired form but in the structure illustrated in the drawing is circular and this opening 9 is adapted to receive the dowel pin 10 which is formed integral with the rear edge of the seat 11 so as to form a support for the seat to prevent the same from movement with relation to the standard.

In order to facilitate the rising of the user a suitable compression coil spring 12 is secured to the lower end of the lower section 4 and it will be seen that when the weight of the occupant is placed on the seat the spring will be compressed and the rising of the occupant will relieve the weight and the spring will assist in lifting the device from the ground.

In use it will be seen that the device is strapped to the body of the user by the belt 8 and when it is occupied it will be apparent that the person sits upon the seat 11 and his weight is supported on the standard 1. In order to insure the comfort of the occupant the foot 4 may be adjusted to a desired height and the belt 8 may be passed through any one of the openings 7 thereby adjusting the distance between the feet and the belt.

While in the foregoing there has been shown and described the preferred embodiment of this invention, it is to be understood that such changes may be made in the combination and arrangement of parts as will fall within the spirit and scope of the appended claim.

What is claimed is:—

A stool of the class described comprising a standard, a seat secured intermediate the

ends of the standard, means for adjusting the height of said standard, the upper end of the standard being provided with a plurality of transverse openings and a belt 5 adapted to be passed through one of said openings to attach the device to the body of the user.

In testimony whereof I affix my signature in presence of two witnesses.

EDWARD BRAGG.
